UNITED STATES PATENT OFFICE.

FREDERICK A. TURNER, OF OKMULGEE, OKLAHOMA.

TEMPER SCREW.

Application filed April 14, 1925. Serial No. 23,156.

This invention relates to temper screws for oil well drilling rigs.

An important object of the invention is to provide a device of this character in which the necessity for the operator's constantly climbing up and down to make adjustments thereof is eliminated.

As is well known to those familiar with the art, in the ordinary type of temper screw, it is necessary that a platform be built upon the derrick floor which is usually known as a three story stool. This platform is arranged adjacent the walking beam and must be ascended each time that the ordinary temper screw is adjusted as to length as it must be at frequent intervals. This not only results in a loss of time but necessitates interruption of drilling and accordingly an important object of this invention is to provide not only a device which may be adjusted without the necessity of ascending the platform for the adjustment, but which may be, if so desired, adjusted while the drilling is being carried on.

A further object of the invention is to provide a device of this character which may be very cheaply and readily produced and which will require no changes whatever in the present drilling apparatus.

These and other objects I attain by the construction shown in the accompanying drawings, wherein for the purpose of illustration is shown a preferred embodiment of my invention and wherein:

Figure 1 is a side elevation partially in section of a temper screw constructed in accordance with my invention;

Figure 2 is a front elevation thereof;

Figure 3 is a perspective of the upper guide for the stem;

Figure 4 is a perspective of the plate forming one bearing for the stem and a portion of the housing for the gearing; and

Figure 5 is a fragmentary side elevation showing a modified form of operating mechanism.

Referring now more particularly to the drawings, the numeral 10 indicates the usual walking beam having its ends slotted, as at 11, and its upper surface notched, as at 12, for coaction with the T head 13 formed upon the yoke 14 of the temper screw. The construction of this T head is in no manner altered. The yoke comprises a substantially rectangular frame having a broad base 15

and vertically extending side walls 16, the lower ends of which are enlarged, as at 17, to the same width as the base. The base and the enlarged portions 17 are connected by side plates 18 and the upper surfaces of the enlarged portions are connected by a top plate 20 which is notched, as at 21, to receive the sides 16 above the enlarged portions 17. The base 15 and top 20 have formed therein aligned openings 22 and 23. Directed through these openings is a worm having at its lower end a head 24 upon which is seated a cross bar 25 notched at its ends, as at 26, for the reception of links 27 of the usual temper screw clamp. The worm adjacent the head and at the point of its passage through this cross bar is preferably squared, as at 28, so that rotation of this cross-bar upon the screw is prevented.

At its upper end, the cross bar is likewise squared, as indicated at 29, and has mounted upon this squared portion and secured in position by a nut 30 of a guide bar 31, the ends of which are notched, as at 32, for slidable engagement with the sides 16 of the yoke. Seated upon the base 15 about the opening 22 is a thrust bearing 33. Engaging this thrust bearing with its lower ends is a worm nut 34 having secured thereto a bevel gear 35. It will be obvious that this worm is held against rotation and is mounted for vertical movement upon the yoke and that this vertical movement can be imparted by rotation of the worm nut 34. Secured to the yoke adjacent the base thereof and extending outwardly therefrom is a brace 36 attached to the yoke at a point spaced from its lower end and inclining outwardly and downwardly therefrom is a second brace 37, the lower end of which is vertically extending, as at 38, and is rigidly secured to the outer end of the brace 36. Aligned openings are formed in this vertically extending portion 38 and the opposed enlargement 17 of the side wall and in these openings is rotatably mounted a shaft 39, the inner end of which has secured thereto a bevel pinion 40 meshing with the gear 35.

The vertical extension 38 of the brace 38 may be of any desired length and has mounted thereon adjacent its lower end means for rotating the shaft 39. In Figures 1 and 2 this means consists of a stub shaft 41 having rotatably mounted thereon a sprocket 42. The outer end of the shaft 39

has a sprocket 43 connected with the sprocket 42 by a chain 44. The sprocket 41 is suitably handled, as at 45, so that it may be rotated. In the form shown in Figure 5, a vertically extending rotatably mounted shaft 46 is provided having at its lower end a handle 47 by means of which it may be rotated and at its upper end a bevel gear 48 meshing with the bevel gear 49 carried by the shaft 39. It will be obvious that by extending the controlling operating elements for a desired distance, the temper screw may be operated from the floor and during the drilling operation if this is found desirable.

15 Attention is directed to the fact that by the construction above described, the ordinary swivel cross bar or drilling clamp hanger is eliminated for the reason that the worm supporting the drilling line does not rotate. In the ordinary construction, where this worm rotates, it is necessary that a swivel be provided to prevent twisting of the drilling line. The swivel alone will not accomplish this purpose and it is necessary to provide in addition to the swivel what is ordinarily referred to as a "jockey stick" one end of which is secured to a fixed part of the derrick or drilling apparatus and the other end of which is secured to the swivel 25 to prevent the same from rotating. This stick during drilling is, of course, reciprocating and is dangerous in that it might become loosened and in falling injure some one upon the derrick floor.

30 25 It will also be obvious that the construction hereinbefore set forth is capable of a considerable range of change and modification without materially departing from the spirit of my invention and I accordingly do not limit myself to such specific structure 35 except as hereinafter claimed.

I claim:—

1. In a temper screw, a yoke provided at its upper end with means for engagement 45 with a walking beam, the yoke embodying spaced arms on the housing connecting the lower ends of the arms of the yoke, a ver-

tically extending worm shaft arranged between the arms of the yoke and having its lower end directed through the housing, a 50 worm nut engaging the worm within the housing and including a gear, brackets carried by the yoke including a vertical extension extending considerably below the lower end of the yoke, a shaft mounted in said 55 bracket and having one end extending into the housing and provided with a gear for engagement with the gear of the worm nut and means at the lower end of the extension of the bracket for rotating said shaft, 60 the upper end of said worm shaft being square and a guide engaged with the squared portion of the worm shaft and having its ends notched for engagement with the arms of the yoke to thereby permit longitudinal 65 movement of the worm shaft and prevent rotation thereof.

2. In a temper screw, a yoke provided at its upper end with means for engagement with a walking beam, the yoke embodying spaced arms on the housing connecting the lower ends of the arms of the yoke, a vertically extending worm shaft arranged between the arms of the yoke and having its lower end directed through the housing, a 70 worm nut engaging the worm within the housing and including a gear, brackets carried by the yoke including a vertical extension extending considerably below the lower end of the yoke, a shaft mounted in said 75 bracket and having one end extending into the housing and provided with a gear for engagement with the gear of the worm nut, means at the lower end of the extension of the bracket for rotating said shaft, including a stub shaft mounted at the lower end of said extension, a sprocket gear mounted on said stub shaft and having a handle whereby it may be rotated, a sprocket gear 80 rotatably mounted in the brackets and a 85 chain connecting said sprockets.

In testimony whereof I hereunto affix my signature.

FREDERICK A. TURNER.
